(57) **CLAIM**

The ornamental design for a display screen with graphical user interface, as shown and described.

DESCRIPTION

FIG. 1 is a front view of a display screen with a graphical user interface showing a first embodiment of our new design; and, FIG. 2 is a front view of a display screen with graphical user interface showing a second embodiment of our new design. The uneven-length broken lines are imaginary lines that represent unclaimed boundaries of our new design. The even-length broken lines showing the remainder of the display screen with graphical user interface are for environmental purposes only and form no part of the claimed design.
